UNITED STATES PATENT OFFICE.

LOUIS TLUCKA, OF LOS ANGELES, CALIFORNIA, ASSIGNOR TO MISSION HOSIERY MILLS, OF LOS ANGELES, CALIFORNIA, A CORPORATION OF CALIFORNIA.

DESIGN FOR A STOCKING.

Application filed August 20, 1928. Serial No. 27,896. Term of patent 14 years.

To all whom it may concern:

Be it known that I, LOUIS TLUCKA, a citizen of the United States, residing at Los Angles, in the county of Los Angles and State of California, have invented a new, original, and ornamental Design for Stocking, of which the following is a specification, reference being had to the accompanying drawing, forming a part thereof.

I claim:

The ornamental design for a stocking as shown.

LOUIS TLUCKA.
